WINDING MACHINE

Robert McC. Johnstone, Bondsville, Pa.

Application January 30, 1942, Serial No. 428,958

21 Claims. (Cl. 242—66)

This invention relates to winding machines, and one object of the invention is to provide improved mechanism for driving the pressure roll which, in machines of the type involved, acts upon the top of the roll of wound material during the winding operation and which is displaced bodily in the frame of the machine as the said roll of wound material increases in diameter.

Another object of the invention is to provide improved means for supporting and guiding the top roll in the machine; for counterweighting the roll; and for adjusting the axial relation of the roll with respect to the winding drums which underlie and support the roll of wound material.

Still another object of the invention is to provide improved guide means for the winding shaft, as hereinafter described, together with novel means for adjusting the said shaft to reduce and compensate for wear occurring as a result of the frictional contact of the shaft with the guides.

The invention further resides in certain structural mechanical details hereinafter described and illustrated in the attached drawings, in which:

Figure 1 is a side elevational view of a winding machine made in accordance with my invention;

Fig. 2 is a section on the line 2—2, Fig. 1;

Fig. 3 is a sectional view on the line 3—3,

Fig. 1;

Fig. 4 is a sectional view on the line 4—4,

Fig. 3;

Fig. 5 is a fragmentary view in perspective illustrating a detail of the counterweighting device;

Fig. 6 is a fragmentary view in perspective showing details of the winding bar guide elements;

Fig. 7 is a section on the line 7—7, Fig. 3;

Fig. 8 is an enlarged fragmentary sectional view illustrating details of the winding bar adjusting device, and

Fig. 9 is a sectional view of the winding bar as though taken on the line 9—9, Fig. 8, but showing an attached core cylinder.

With reference to the drawings, the machine comprises the usual frame 1 in which are journaled the conventional front and rear winding drums 2 and 3 which support the work roll 4 of wound material. Also supported in the frame for vertical displacement is a top pressure roll 5 which acts upon the top of the roll 4, as illustrated. The frame also provides a journal support for a master roll 6 from which the wound material, in the form in the present instance of a paper web 7, is drawn. The roll 4 is built up

upon a winding shaft 8, this shaft being held in vertical guides 9, 9, which are operatively connected with the top pressure roll 5, as hereinafter described, and which are vertically movable in the frame 1 of the machine with the said top roll. The web 7 is guided to the winding shaft 8 by guide rolls 11 and 12 and by the front winding drum 2, as illustrated.

The drums 2 and 3 are driven through a shaft 13, which is connected to a suitable source of power (not shown). The shaft carries two pinions 14 and 15 which mesh respectively with gears 16 and 17 on the projecting trunnions 18 and 19 of the drums 2 and 3. The trunnion 19 of the roll 3 also carries a bevel gear 21 which meshes with a bevel gear 22 at the lower end of a vertical shaft 23 journaled in the frame, said shaft having secured thereto an elongated pulley 24 which extends to the top of the machine, as illustrated. Engaging this pulley is a belt 25, and this belt also engages a pulley 26 secured to a stub shaft 27 journaled, as best illustrated in Fig. 2, in a bracket 28 which is slidably supported on a vertical guide 29 on the frame 1. A corresponding bracket 31 is similarly slidably supported at the opposite side of the machine on a guide 32, and these brackets provide journals 33 for the opposite ends of the top pressure roll 5. One trunnion of the roll 5 carries a bevel gear 34 which meshes with a bevel gear 35 at the lower end of the shaft 27. In this manner, a driving connection is established between the bevel gear 21 of the rear winding drum 3 and the top pressure roll 5.

As best shown in Figs. 3 and 4, the belt 25 is tightened on the pulleys 24 and 26 by means of an idler pulley or roller 36. This roller is supported on one end of a lever 37 which is pivotally secured at 38 to the bracket 28, and a spring 39 connected to the opposite end of the lever exerts pressure tending to move the lever on its pivot so as to force the idler pulley 36 against the belt, thereby to tighten the belt, as in Fig. 4. Secured to the lever is a pivoted latch 41, the jaw 42 of which is arranged to engage a flange 43 on the bracket 28 when the lever is moved about its pivot against the pressure of the spring 39 so as to retract the idler pulley 36 from the belt 25; and a spring 44 connected to the latch tends to draw and to retain the latch in an operative position with respect to the said flange. A handle 45 is provided on the end of the lever 37 so that the lever may be moved manually into position to engage the latch-lever; and in order to again tighten the belt 25, it is only necessary to move

the forward end of the latch 41 to the left, as viewed in Fig. 4, to thereby release the latch and to permit the spring 39 to shift the lever 37 to the belt-tightening position.

Extending upwardly from each of the brackets 28 and 31 is a sprocket chain, 46 and 47 respectively. These chains pass over sprockets 48, 48 on a shaft 49 journaled at the top of the frame, and downwardly at the back of the machine to sprockets 51 and 52 journaled in the lower part of the frame. From the sprockets 51 and 52 the chains extend upwardly and are attached to the respective brackets 28 and 31. A shaft 53, which carries the sprocket 51, carries also a sprocket 54, and this sprocket is connected through a chain 55 with a sprocket 56 on a shaft 57 journaled in the frame 1. The shaft 57 carries a hand wheel 58, and is also provided with a ratchet 59 which is engaged by a retractable detent 61. By turning the hand wheel 58 in a counterclockwise direction, as viewed in Fig. 1, the chains 46 and 47 may be actuated to elevate the brackets 28 and 31, and with them the top pressure roll 5. For such adjustment, the belt 25 may be loosened on the pulley 24 by actuation of the lever 37, as previously described. It will be noted that the pulley 26 is flanged, so as to retain the belt 25, and that there is also provided on the bracket 28 a guard 62 which partially embraces the belt and the pulley 24, and which is also flanged so as to guide the belt in its normal horizontal position and to prevent its binding on the pulley 24 when the top roll 5 is elevated, as described.

During the winding operation the roll 5 is displaced vertically by the increasing diameter of the roll 4. This elevation of the roll 5 occurs while the belt 25 is tight upon the pulleys 24 and 26. This upward movement, however, is relatively slow, and the belt 25 readily adjusts itself on the pulley 24 in accordance with the upward movement of the flanged companion pulley 26.

It will be noted that the shaft 49 carries at one end a pulley 63, to which is secured and around which passes a cable 64, the lower end of which carries a counterweight 65. This counterweight is adjusted to counterbalance a portion of the weight of the top pressure roll assembly. It will be noted also that the ratchet and detent 59—61, while engaged, permit elevation of the top pressure roll 5 as described above, but prevent a reverse movement, and, therefore, function to releasably retain the roll 5 in the elevated position.

The manner in which the chain 47 is secured to the bracket 31 is illustrated in Fig. 5. Secured to the bracket is a U-shaped element 66, within which is secured, by means of screws 67, 67, a block 68 to which the chain is attached as shown. The screws 67 pass through slots 69 in the block 68, so that when the said screws are loosened, the element 66 and the bracket 31 to which the said element is attached may be adjusted vertically with respect to the block and to the chain 47. Such vertical adjustment may be conveniently effected through the medium of screws 71 and 72 threaded into the top and bottom respectively of the member 66, and bearing respectively against the top and bottom surfaces of the block 68. By means of this adjustment, and the resultant relative adjustment of the journals 33, the top feed roll 5 may be brought into true parallelism with the drums 2 and 3.

Depending from each of the brackets 28 and 75

31 in the manner best illustrated in Fig. 6 is a bar-like extension 73, each of these bars having in its inner face a longitudinal slot 74 which receives the trunnions 75 of the winding shaft 8, and which, therefore, guides the said shaft in its vertical movement. At the bottom of at least one of the slots 74 is a transverse slot 76, through which the trunnion may be admitted and withdrawn from the slot. The bars 9, which are rectangular in shape, extend downwardly through a socket 77, which in each instance is secured to the upper end of a rod 78, each of said rods extending slidably through an aperture 79 in the transverse flange 81 of the frame 1. The socket 77 is closely fitted to the bar 73 and acts as a guide for the latter. When the rods 78 are in their lowermost position, as shown in Fig. 3, the sockets 77 rest upon the top of the flange 81. The bar 73 being free to slide in the socket may now move upwardly or downwardly independently of the rods 78. As the bar 73 moves upwardly in the socket, however, the said socket is eventually engaged by a flange 82 projecting transversely from the lower end of the bar 73, so that further upward movement of the bar 73 will result in an elevation of the rod 78 in the frame 1. The rod 78 thus assumes the function of a sliding guide for the lower end of the bar 73. By this use of the telescoping elements 73 and 78, the bars 73 may be made sufficiently short so that in the lowermost position of the top pressure roll 5, the lower ends of the bars 73 will still lie above or at the floor level, thereby avoiding the necessity for a pit in the floor for accommodation of the lower end of the guide bar.

In order to reduce to a minimum the wear occurring in the trunnions 75 as a result of frictional contact with the walls of the guide slot 74, and to afford means for compensating for the wear that unavoidably must occur, I prefer to form the shaft 8 as illustrated in Figs. 7, 8 and 9. The body 83 of the shaft is rectangular in form, as illustrated. This rectangular form provides for applying to the shaft a cylindrical core 84, of wood for example, which forms the base for the roll 4, the corners of the rectangular shaft entering the relatively soft wood of the core, as shown in Fig. 9, and thereby solidly connecting the core with the shaft, while at the same time providing for eventual withdrawal of the shaft axially from the core after the latter has received the wound material, said core remaining in the roll. Within the ends of the hollow body 55 83 of the shaft I insert cylindrical trunnion elements 85 and 86, these elements being provided in each instance with a thrust bearing 87 and radial bearings 88 of the needle type. Each of the elements 85 and 86 is provided with a relatively fixed collar 89 which separates the bearings 88; and a snap ring 91 is provided in the body to retain the trunnion elements through the medium of the adjoining bearing 88 and the collar 89 in the body member 83. At one end 60 of the shaft and as shown in Fig. 8, the inner race of the thrust bearing 87 is supported on a screw 92 which is threaded into the body 83 of the shaft and which, therefore, is axially adjustable in the latter. This screw may be locked 65 in a given adjusted position in the body 83 by a set screw 93. The head of the screw 92 is provided with a socket 94 for reception of a wrench 95, which may be inserted through the trunnion element 85, which in this instance is hollow, whereby the screw 92 may be turned for axial

adjustment in the body. The outer race of the thrust bearing 87 seats against the inner end of the element 85, and this element is supported on suitable radial bearings, as described above. This device thereby provides for adjustment of the trunnion element 85 axially of the body 83 of the shaft to compensate for any wear occurring at the outer ends of the trunnions. Obviously both of the trunnion elements may be made adjustable if desired.

It will be noted further, see Fig. 6, that the outer extremities 75 of the trunnion elements 85 and 86, which extremities fit into the guide slots 74, are made flat at the sides and are fitted closely between the side walls of the slots so as to be held against rotation. The body 83 of the shaft may rotate freely on the anti-friction bearings 88; and by rendering the trunnions non-rotatable, the frictional wear with the guide bar 73 is solely that resulting from the relatively slow sliding movements of the trunnions in the guide slots and is thereby held at a minimum.

The elongated pulley and belt drive previously described has a material beneficial effect upon the top pressure roll action. This is due in part to the free travel of the belt axially of the said pulley and the avoidance thereby of resistance to the normal upward displacement of the top roll by the roll 4 of wound material. This almost complete absence of resistance by the roll-driving means insures uniform displacement at both ends of the top roll, and maintenance by the top roll of substantially uniform pressure throughout its length upon the roll 4.

I claim:

1. In a winding machine of the type comprising winding drums and a top pressure roll bodily displaceable with respect to said drums; a pulley operatively connected to and movable with said top roll, a driven pulley, one of said pulleys being elongated and axially paralleling the path of said displacement, and a belt connecting said pulleys.

2. In a winding machine of the type comprising winding drums and a top pressure roll bodily displaceable with respect to said drums; an elongated driven pulley paralleling the path of said displacement, a second pulley operatively connected to and movable with said top roll, and a belt connecting said pulleys.

3. In a winding machine of the type comprising winding drums and a top pressure roll bodily displaceable with respect to said drums; a pulley operatively connected to and movable with said top roll, a driven pulley, one of said pulleys being elongated and axially paralleling the path of said displacement, a belt connecting said pulleys, means for selectively tightening and loosening the belt on the pulleys, and means for manual displacement of the top roll.

4. In a winding machine of the type comprising winding drums and a top pressure roll bodily displaceable with respect to said drums; a pulley operatively connected to and movable with said top roll, a driven pulley, one of said pulleys being elongated and axially paralleling the path of said displacement, a belt connecting said pulleys, means for preventing axial displacement of the belt on one of the pulleys, and guide means for the belt relatively fixed with respect to the last-named pulley and operative with respect to the other pulley.

5. In a winding machine of the type comprising winding drums and a top pressure roll bodily dis-

placeable with respect to said drums; a pulley operatively connected to and movable with said top roll, a driven pulley, one of said pulleys being elongated and axially paralleling the path of said displacement, a belt connecting said pulleys, means for preventing axial displacement of the belt on one of the pulleys, and guide means for the belt relatively fixed with respect to the last-named pulley and embracing the other pulley.

6. In a winding machine of the type comprising winding drums and a top pressure roll bodily displaceable with respect to said drums; a pulley operatively connected to and movable with said top roll, a driven pulley, one of said pulleys being elongated and axially paralleling the path of said displacement, a belt connecting said pulleys, and means for selectively tightening and loosening the belt on the pulleys, said means comprising a pivoted lever carrying a roller for engagement with the belt at a point intermediate the pulleys, a spring tending to move the lever to a position in which the roller is retracted with respect to the belt, and a spring-actuated latch on the lever for releasably retaining the lever in a position in which the roller is advanced and operative with respect to the belt.

7. In a winding machine of the type comprising winding drums, a top pressure roll bodily displaceable with respect to the drums, and a winding shaft intermediate the drums and the roll for reception of the material to be wound; guide means for said shaft movable with the top roll, said means comprising a first member attached to the top roll, a second member constituting a guide for and comprising means for limiting the extent therein of the movement of the first member, and means for guiding the said second member for movement in the direction of top roll displacement, said second member remaining at all times within its guide means.

8. In a winding machine of the type comprising a frame, winding drums journaled in the frame, a top pressure roll bodily displaceable in the frame with respect to the drums, and a winding shaft intermediate the drums and the roll for reception of the material to be wound; a guide member for said shaft movable with the top roll, and a telescopic extension for said member having sliding engagement with and guided continuously in said frame.

9. In a winding machine of the type comprising winding drums, a top pressure roll bodily displaceable with respect to the drums, and a winding shaft intermediate the drums and the roll for reception of the material to be wound; guide rails engaging the ends of said shaft so as to preclude axial displacement of the latter, and means for adjusting the shaft as to length so as to maintain a close fit between the said rails and the ends of the shaft.

10. In a winding machine of the type comprising winding drums, and a winding shaft for reception of the material to be wound and displaceable with respect to the drums; guide means at opposite ends of the shaft, trunnions on the shaft engaged with said guides, and means for adjusting at least one of said trunnions axially in the shaft.

11. In a winding machine of the type comprising winding drums, and a winding shaft for reception of the material to be wound and displaceable with respect to the drums; guide means at opposite ends of the shaft, trunnions on the shaft

engaged with said guides, one at least of said trunnions being hollow and being longitudinally adjustable in the shaft, and a screw threaded into the shaft and forming an adjustable abutment for the inner end of the trunnion, said screw being accessible through the hollow trunnion for axial adjustment in the shaft.

12. In a winding machine of the type comprising winding drums, and a winding shaft for reception of the material to be wound and displaceable with respect to the drums; guide means at opposite ends of the shaft, trunnions on the shaft engaged with said guides, one of said trunnions being hollow and being journaled for rotation in the shaft, a thrust bearing for the inner end of the trunnion, and means accessible for actuation through the hollow trunnion for axially adjusting the said bearing in the shaft.

13. In a winding machine of the type comprising a frame, winding drums journaled in the frame, a top pressure roll bodily displaceable with respect to said drums, and journal blocks for said roll guided in the frame; a shaft journaled in the upper part of the frame, a pair of sprockets on the shaft, a corresponding pair of sprockets in the lower part of the frame, a chain engaged with each companion set of upper and lower sprockets and connected respectively to the said journal blocks, and means for adjusting one of the journal blocks with respect to and longitudinally of its chain.

14. In a winding machine of the type comprising a frame, winding drums journaled in the frame, a top pressure roll bodily displaceable with respect to said drums, and journal blocks for said roll guided in the frame; a shaft journaled in the upper part of the frame, a pair of sprockets on the shaft, a corresponding pair of sprockets in the lower part of the frame, a chain embracing each companion set of upper and lower sprockets and connected respectively to the journal blocks, and a counterweight connected to the shaft.

15. In a winding machine of the type comprising a frame, winding drums journaled in the frame, a top pressure roll bodily displaceable with respect to said drums, and journal blocks for said roll guided in the frame; a shaft journaled in the upper part of the frame, a pair of sprockets on the shaft, a corresponding pair of sprockets in the lower part of the frame, a chain engaged with each companion set of upper and lower sprockets and connected respectively to the said journal blocks, means for manual rotation of one of said lower sprockets, means for adjusting one of the journal blocks with respect to and longitudinally of its associated chain, and counterbalance means connected with the shaft.

16. In a winding machine of the type comprising winding drums, and a winding shaft for reception of the material to be wound and displaceable with respect to the drums; guide means at opposite ends of the shaft, and trunnions journaled in the ends of the shaft and non-rotatably engaged with said guides.

17. In a winding machine of the type comprising winding drums, and a winding shaft for reception of the material to be wound and displaceable with respect to the drums; guide means at opposite ends of the shaft, trunnions journaled in the ends of the shaft and slidably engaged in said guides, and means preventing rotation of the trunnions in the guides.

18. In a winding machine of the type comprising winding drums, and a winding shaft for reception of the material to be wound and displaceable with respect to the drums; guide means at opposite ends of the shaft, trunnions journaled in the ends of the shaft and non-rotatably engaged with said guides, and means for axially adjusting at least one of the trunnions in the shaft.

19. In a winding machine of the type comprising winding drums, and a winding shaft for reception of the material to be wound and displaceable with respect to the drums; guide means at opposite ends of the shaft, trunnions journaled in the ends of the shaft and slidably engaged in said guides, means preventing rotation of the trunnions in the guides, and means for axially adjusting at least one of the trunnions in the shaft.

20. In a winding machine of the type comprising winding drums, a top pressure roll bodily displaceable with respect to the drums, and a winding shaft intermediate the drums and the roll for reception of the material to be wound; guide means at opposite ends of the shaft, trunnions on the shaft engaged with said guides, and means for adjusting one of said trunnions axially in the shaft.

21. In a winding machine of the type comprising winding drums and a winding shaft for reception of the material to be wound and displaceable with respect to the drums; guide means at opposite ends of the shaft, and trunnions journaled on the ends of the shaft and non-rotatably engaged with said guides, a thrust bearing at the inner end of each of said trunnions, and means for adjusting at least one of said thrust bearings longitudinally in the shaft.

ROBERT McC. JOHNSTONE.
